UNITED STATES PATENT OFFICE

GLENN S. RAVEN, OF BUFFALO, AND FRANK T. BOWEN, OF LOCKPORT, NEW YORK

DESIGN FOR A HEDGE TRIMMER OR SIMILAR ARTICLE

Application filed March 29, 1929. Serial No. 30,682. Term of patent 14 years.

To all whom it may concern:

Be it known that we, GLENN S. RAVEN and FRANK T. BOWEN, citizens of the United States, residing at Buffalo, in the county of Erie and State of New York, and Lockport, in the county of Niagara and State of New York, respectively, have invented a new, original, and ornamental Design for a Hedge Trimmer or Similar Article, of which the following is a specification, reference being had to the accompanying drawings, forming part thereof.

In the accompanying drawings:

Figure 1 is a perspective view of a hedge trimmer or similar article showing our new design.

Figure 2 is a top plan view thereof.

Figure 3 is an end elevation of the same when viewed from the left of the disclosures in Figs. 1 and 2.

We claim:

The ornamental design for a hedge trimmer or similar article, as shown.

GLENN S. RAVEN.
FRANK T. BOWEN.
